CLAIM

The ornamental design for a pet feeding bowl, as shown and described.

DESCRIPTION

FIG. 1 is a top, front, left isometric view of the pet feeding bowl of the present invention;

FIG. 2 is a top, rear, right isometric view thereof;

FIG. 3 is a top plan view thereof;

FIG. 4 is a right-side view thereof;

FIG. 5 is a left-side view thereof;

FIG. 6 is a front view thereof; and,

FIG. 7 is a rear view thereof.

The broken lines illustrate portions of the pet feeding bowl that form no part of the claimed design.
